UNITED STATES PATENT OFFICE

PERCIVAL W. JONES, OF WARWICK, RHODE ISLAND, ASSIGNOR TO ROSENHEIM CO. INC.,
OF PROVIDENCE, RHODE ISLAND, A CORPORATION OF RHODE ISLAND

EXTENSION DEVICE

Application filed February 6, 1929. Serial No. 337,837.

This invention relates to an extension device of the type interposed in a wrist watch strap; and has for its object to provide an improved means for retaining the sections 5 in folded position.

A further object of the invention is the constructing of the sections so that they may nest one within the other and be of minimum thickness when the device is in 10 folded position.

A still further object of the invention is the provision of an easily releasable clamp for securing one of the straps to its section.

With these and other objects in view, the 15 invention consists of certain novel features of construction, as will be more fully described, and particularly pointed out in the appended claims.

In the accompanying drawings:

20 Fig. 1 is a top plan view of the extension device in folded position.

Fig. 2 is a top view of the extension device in extended position showing the different sections as hinged together.

25 Fig. 3 is a sectional side view of the device unfolded, as illustrated in Fig. 2.

Fig. 4 is a sectional view showing the device partially folded.

Fig. 5 is a sectional view showing the device 30 as completely folded in clasped position.

Fig. 6 is a sectional end view of the device in folded position taken on line 6—6 of Fig. 5.

Fig. 7 is a perspective view of the end of 35 the cover section showing one portion of the clamp.

Fig. 8 is a perspective view of the clamp which is associated with the portion shown in Fig. 7.

40 Fig. 9 is a perspective view showing the parts of Figs. 7 and 8 in assembled position.

Fig. 10 is a sectional view through the pivoting trunnions of Fig. 9.

Fig. 11 is a sectional view of the assembly 45 of Fig. 9.

Fig. 12 is a fragmental perspective view of a modification of the end section.

Fig. 13 is a perspective view of the clamp associated therewith.

50 Fig. 14 is a section of the modified end

section with the clamp assembled therewith.

It is found in the use of wrist watch bracelets desirable to provide an extension device which may be unfolded to temporarily lengthen the wrist-encircling size of the 55 strap to permit it to be passed over the hand of the wearer and to provide such a construction which may have the desired unfolding action and yet be firmly secured in folded position against usual unfolding

strains and to accomplish these results I have provided a pair of inturned end fingers spaced from the top wall of the cover section and have so shaped the end edges 60 of the body section as to snap between these fingers, and the top wall of the cover section to lock the parts in closed position, and in order that the sections may lie close 65 one to the other, I have provided a pair of links to fit between the opposite walls of a pair of sections so that they will not overlap one another to increase the thickness of 70 the device. I have also provided a novel means for securing and adjusting of the strap to one of the sections, consisting of 75

providing a clamping edge on the section itself with a pivotally mounted shoe to receive between it and the clamp edge the strap to be attached thereto; and the following is a detailed description of the present embodiment of this invention illustrating the preferred means by which these advantages results may be accomplished:

With reference to the drawings, 12 designates the body section which is of channel shape in cross section, having an outer wall 13 and opposite side walls 14. At one end 80 of this body section there is pivoted at 15 a plate section 16, which is hinged at 17 to a second plate section 18, both of 85 which may be folded one upon the other to house in the channel section 12, as is illustrated in Fig. 4.

The plate section 18 is of a length greater 90 than the body section 14 and on that portion 19 thereof which extends beyond the end of the body section 12 when in folded position, I have provided a pair of spaced flanges 20, between which there is pivoted a gripper 21 having a camming edge 22 to bind between 95 100

this edge and the plate 18, one end 23 of a suitable strap 24, as illustrated in Fig. 1.

The cover section 25 is of channel shape in cross section having an outer wall 26 and side walls 27, and is connected to the body section by an intermediate section formed of a pair of links 28 pivoted as at 29 and 30 to the respective side walls 14 and 27 of these two sections so as to swing thereover and cover the plate sections 16 and 18 when folded therein.

This cover section 25 is of a width greater than the body section so that its channel walls 27 will not only receive between them the channel walls 14 of the body section, but will also receive between them the links 28 to lie between the side walls of the sections so that all of the parts nest one within the other and the links 28 will not overlie the plate sections 16 and 18 to increase the thickness of the device when in folded position, but rather will merely tend to increase the general width of the device by a dimension equal to the thickness of the sheet stock from which they are formed.

The cover section is extended at its free end 31 with a downwardly turned jaw 32, and on the sides of this extension trunnions 33 are provided to pivotally mount a shoe 34 having a strap engaging surface 35 with flanges 36 to receive in openings 37 the trunnions 33. When the shoe is in the position illustrated in Figs. 3, 4 and 9, the strap end 40 will be held between the jaw 32 and the strap engaging surface 35 to feasably secure this end of the strap to the device.

For some constructions, however, I prefer to reduce the end portion of the end section, as illustrated at 41 in Fig. 12, to conform to the appearance of one of the links of the strap which is flanged at 42 with openings 43 therein to receive the trunnions 44 of the gripper 45 which operates in the same manner as the gripper 21 on the opposite end section.

In order that the sections may be retained in folded position, I have provided a pair of fingers 38 on the end edges of the side walls 27 of the cover section, which extend toward each other. These fingers 38 are positioned at a point spaced from the top or outer wall of this section and receive in this space the rounded ends 39 of the edges of the side walls 14 to firmly clamp the two channel sections together.

It will be understood that there is sufficient resiliency in the inturned fingers thus formed to permit of snapping and unsnapping of the sections to and from folded position for the desired purposes hereinbefore mentioned.

The foregoing description is directed solely towards the construction illustrated, but 65. I desire it to be understood that I reserve

the privilege of resorting to all the mechanical changes to which the device is susceptible, the invention being defined and limited only by the terms of the appended claims.

I claim:

1. In an extension device, a plurality of sections, means for connecting said sections together to permit folding one on the other, one section having an outer wall and spaced side portions, said spaced side portions having fingers extending therefrom toward each other and spaced from the outer wall and another of said sections having portions at its free end to snap between said fingers and said outer wall due to resiliency of said fingers in a direction longitudinally of the device.

2. In an extension device, a channel shaped body having an outer wall and side walls, a cover section channel shaped in cross section and having an outer wall and side walls, an intermediate section hingedly attached to said sections to permit folding of the channel sections one on the other, fingers extending toward each other from the free end edges of the opposite side walls of one of said channel sections and spaced from its outer wall, the free end edges of said other channel section having rounded nose portions to snap between said fingers and said outer wall by resiliency of said fingers in a direction longitudinally of the device and hold said sections in folded position.

3. In an extension device, a channel-shaped body section having an outer wall and side walls, a cover section channel-shaped in cross section having an outer wall and side walls, a pair of links hingedly connecting said sections to permit folding of the sections one on the other, fingers extending toward each other from the free end edges of the opposite side walls of one of said channel sections and spaced from said outer wall, the free end edges of the other channel section having rounded nose portions to resiliently snap between said fingers and said outer wall by resiliency of said fingers in a direction longitudinally of the device and hold said sections in folded position.

4. In an extension device, a plurality of sections, means for connecting said sections together to permit folding one on the other, one end section having means for attaching a strap thereto, comprising a downwardly-turned lip on the edge of said section, and a member pivoted on the section to swing towards and from said lip to press the strap into direct clamping engagement with the edge of said lip.

5. In an extension device, a plurality of sections, means for connecting said sections together to permit folding one on the other,

one end section extending beyond another section when in folded position and having a lip extending at an angle thereto, and a member on the section pivoted to swing towards and from said lip to press the strap into direct clamping engagement with the edge of said lip.

5 6. In an extension device, a plurality of sections, means for connecting said sections together to permit folding one on the other, one end section extending beyond the other section when in folded position and having a lip extending at an angle thereto, trunnions extending from both sides of said extension, a plate having side ears with openings therein adjacent the end edge of the plate to receive said trunnions and pivotally mount the same to swing and receive between it and the lip a strap to be attached thereto, to press the strap into direct clamping engagement with the edge of the lip.

10 20 In testimony whereof I affix my signature.
PERCIVAL W. JONES.
